UNITED STATES PATENT OFFICE.

FREDRIC CANDEE WEIR AND NATHANIEL O. GOLDSMITH, OF CINCINNATI,
OHIO, ASSIGNORS TO THE WEIR FROG COMPANY, OF SAME PLACE.

CABLE AND RAILWAY CROSSING.

SPECIFICATION forming part of Letters Patent No. 402,875, dated May 7, 1889.

Original application filed May 24, 1888, Serial No. 274,912. Divided and this application filed October 18, 1888, Serial No. 288,477. (No model.)

To all whom it may concern:

Be it known that we, FREDRIC CANDEE WEIR and NATHANIEL O. GOLDSMITH, citizens of the United States, and residents of Cincinnati, in the county of Hamilton and State of Ohio, have invented certain new and useful Improvements in Cable and Railway Crossings, of which the following is a specification.

Our invention relates to a combined cable and railway crossing.

The object of this invention is to provide a strong, durable, and effective crossing, wherein the slot-rails and the railway-rails are firmly secured together and supported.

15 The features of our invention will be fully set forth in the description of the accompanying drawings, making a part of this specification, in which—

Figure 1 is a side elevation of the railway-rails and their supports, showing the T-rails and cable-road rails in section. Fig. 2 is a section at right angles to Fig. 1. Fig. 3 is a detail view of one of the parts. Fig. 4 is a modified form of slot-rails.

25 1 1 represent the slot-rails.

2 represents the center or side bearing girder cable-rails.

3 represents one of the ordinary T-rails of a crossing. It is necessary to thoroughly support the steam-railway rails, to prevent as much as possible the strains upon the cable-rails. This we preferably accomplish by means of I-beams 4 and 5, the I-beam 4 being continuous and forming the substructure of the 35 railway-support, as shown in Figs. 1 and 2. The I-beams 5 are bolted firmly to the I-beam 4 and cut it so as to form an opening or passage, 6, under the slot-rails. In order to support the rails 3 and to sustain the weights on

40 the structure supporting them, we connect the slot-rails to the T-rails by means of knees 7, to one angle of which are bolted firmly the T-rails 3 by bolts 8, the other arm being firmly connected to the slot-rail by bolts 9. Similar 45 knees and bolts are employed to connect the girder-rails to the T-rails. It is desirable to have the heads of the cable-railway rails and the steam-railway rails on the same plane. To accomplish this we slot or gain out the T-

rails to receive the head of the railway-rails 2, 50 and the remaining portion of the T-rail 4 may be cut away, as shown in Fig. 4, so as to abut against the side of the slot-rail; or the slot-rails 1 may be cut away sufficiently to allow the entire portion of the T-rail to project through 55 the gain cut in the slot-rail. This gain is cut sufficiently wide to provide a space, 10, on one side of the T-rail, as shown in Fig. 2, for the passage of the flanges of the car-wheel. Either form shown in Fig. 2 or 4 may be employed, 60 as the knee-brace and I-beams and the built-up structure 4 and 5 furnish sufficient support for the crossing of the slot-rails.

In order to more effectually support the flange of the slot-rail, we provide a stiffening-piece, 11, which is bolted to the under side of the slot-rails by means of rivets or bolts 12. This stiffening-piece 11 is notched at 13, corresponding to the space 10, occupied by the flanges of the car-wheels. The notch 14 in said 70 filling-piece is made to receive the head of the T-rail, (indicated at 15.)

We do not claim, broadly, herein the notches of the slot-rails to receive the head or any portion of the railway-rails, or any portion of the 75 railway-rails lying within the slots or gains, as that is made a subject-matter of our application, Serial No. 274,912, filed May 24, 1888, this being a subdivision of said application with modifications.

It is manifest that the method of construction is adapted to any street-railway or cable railway crossing cable railways as well as steam-railways; but for convenience of illustration we have shown a steam-railway rail 85 crossing cable-railway rails, as this form of construction requires a more solid construction and firmer support.

Having described our invention, what we claim is—

1. A railway-cable crossing composed of the steam rails cut in sections and fitting the slot and tram rails and supported by the sectional I-beam girders 5 upon either side of the slot-rails 1, and a continuous girder, 4, having the 95 cable-grip space 6, substantially as herein specified.

2. A cable-railway crossing composed of the

steam rails cut in sections and fitting the slot and tram rails and supported by sectional I-beam girders 5, and a continuous girder, 4, rigidly connected to the sectional girders 5, substantially as herein specified.

3. A cable-railway crossing composed of the crossing-rail cut in sections abutting and fitting the edges of the slot-rails and lying between the girder-rails which abut the same upon either side, and said sections being firmly connected to the girder-rails at the crossing angles and supported by a continuous girder forming a substructure under the crossing, substantially as specified.

15 4. A cable-railway crossing composed of the

crossing-rails cut in sections abutting and fitting the slot and tram rails, to which they are firmly connected at the crossing-angles by knee-braces, the said crossings being supported by sectional girders divided under the slot-rails to form a grip-space and supported by a continuous under girder, substantially as herein specified. 20

In testimony whereof we have hereunto set our hands.

FREDRIC CANDEE WEIR.
NATHANIEL O. GOLDSMITH.
